UNITED STATES PATENT OFFICE.

WALTER P. OSGOOD, OF MALDEN, MASSACHUSETTS, ASSIGNOR TO THOMAS J. EDWARDS,
OF MELROSE, MASSACHUSETTS.

EMBOSSING-MACHINE.

1,252,299.

Specification of Letters Patent. Patented Jan. 1, 1918.

Application filed January 2, 1915. Serial No. 13.

To all whom it may concern:

Be it known that I, WALTER P. Osgood, a citizen of the United States, residing at Malden, in the county of Middlesex, State of Massachusetts, have invented a certain new and useful Improvement in Embossing-Machines, of which the following is a specification, reference being had therein to the accompanying drawings.

10 The invention comprises various improvements in embossing or printing machines. The said improvements are designed more particularly for use in embossing or printing in gold, silver, and other transfer material, 15 including color, upon leather and other material, as for instance upon parts of shoes and upon hat bands, belts, stays, and the like, although they are not necessarily restricted to such use in all cases. The invention includes various novel combinations and 20 features of construction.

The improvements comprised in the invention are illustrated in a convenient form of embodiment in the accompanying drawings, in which—

Figure 1 is a side elevation, partly broken away, of a machine containing the said embodiment.

Fig. 2 is a front elevation of the said machine.

Fig. 3 is a rear elevation thereof.

Fig. 4 is a view in vertical section mainly in the plane indicated by the line 4, 4, of Fig. 2.

35 Fig. 5 is a view similar to Fig. 4 but showing the ram closed against the die.

Fig. 6 is a view of the lower feed-roll and its shaft or arbor, with the said roll in longitudinal section.

40 Having reference to the drawings,—

The illustrated machine is shown constructed with a frame comprising a base 1 and opposite parallel vertical side-cheeks 2, 2. The operating shaft 3 of the machine is mounted in bearings in connection with the said cheeks. In practice, the said shaft will have combined therewith suitable driving connection and start-and-stop devices arranged to enable the machine to be started 45 at the will of the operator, and to cause the same to stop automatically at the end of a single rotation of the shaft 3, substantially as in the case of various known machines.

The more important parts of the machine 50 include the presser or ram 4 and means for

operating the same from the shaft 3, the die 5 coöperating with the said presser or ram to make the impression or imprint, a heater 6 (Figs. 4 and 5) in connection with the said die, guides at A and B for the strip, a, of transfer material, which are located respectively at the arriving side of the ram and die and the departing side thereof, a pull-off device 7 (Figs. 1, 3, 4 and 5) for facilitating the advance of the said strip to the working 65 point and through the machine, and feed-rolls 8, 9, for the strip.

As shown in Figs. 1, 4 and 5, the die 5 is fixed to the under side of a forwardly projecting portion of a die-support 5^a that is 70 secured at the rear of such portion by bolts 5^b, 5^b, to the tops of the cheeks 2, 2, of the machine-frame. Thereby the die is mounted in position to coöperate with the movably mounted ram 4. The space around and in 75 front of the said forwardly projecting portion of the die-support, and the die, is clear and unobstructed so as to permit the article or material which is to be embossed or printed to be presented and applied from the 80 front in position for the embossing or printing operation, as well as to permit the portions thereof which are not to be embossed or printed to extend laterally at both sides of the die and its support, or to surround 85 the die and its support as in the case of the upper of a shoe which is to be embossed or printed upon its inner surface. The die-support and the die are shown inclined downward and forward, which inclination is 90 regarded as a preferable feature of construction, inasmuch as it permits the required portion of the work to be passed in between the die and the ram by an upward and rearward movement, and other portions thereof 95 to hang down in front of the ram and the adjacent parts of the machine.

The manner and means of attaching the die 5 to the die support 5^a may vary in practice. In the present instance it is shown as 100 having its back placed against the under face of the forwardly projecting portion of the die-support 5^a, and as being clamped in place through being engaged at its ends by downwardly projecting portions of flanges 105 formed on screws 5^m, 5^m, Figs. 1 and 2, the stems of the said screws entering threaded holes tapped in the opposite sides of the said portion of the die-support. For convenience in setting or positioning the die upon the 110

die-support a gage 5^a, Fig. 1, is applied to the said portion of the die-support at the rear of the place for the die. The said gage is furnished at its opposite ends with ears or lugs fitting against opposite side-faces of the die-support and slotted at 5^b to accommodate the stems of the screws 5^c which fasten the gage to the die-support. The slots 5^b permit the gage to be shifted in the direction from front to rear, and vice versa, in making adjustment of the gage. In applying the die to the die-support the rear edge of the die is placed against the gage.

For the heating of the die, as required for some classes of work, the die-support 5^a has combined therewith the heater 6. The latter is in this instance an electric heater, although the precise character and construction of the heater is not in all cases material, and I contemplate in practice varying the character, construction, and manner and place of application of the same. As herein shown the electric heater 6 is contained within a chamber in the die-support, Figs. 4 and 5, the wiring for the heater being indicated at 6^a. The die-support is made of heat-conducting material, so that the heat may reach the die attached thereto, and for the purpose of preventing loss and waste of heat by conduction to the machine-frame heat insulating material 6^b is interposed between the die-support and the portions of the cheeks 2, 2, to which said die-support is applied, washers of such material (shown best in Fig. 1) also being interposed between the heads of the bolts 5^b and the upper surface of the die-support. A suitable switch and rheostat (not shown) will be included in the electric connections of the heater in practice for the purpose of controlling the heating and the degree of heat.

The closing together of the ram and die for the embossing or printing operation, and subsequent separation and opening to permit removal of the embossed work or material are provided for by mounting the ram upon a movable support and operatively combining the said support with an eccentric upon the operating shaft 3. In addition, provision is made for a yielding action of the ram in closing toward the die. The illustrated machine embodies ram-supporting and actuating devices arranged to provide for the said yielding action and embodying certain of the improvements which are comprised in the present invention. A different construction and arrangement of the actuating devices may be provided in practice, in case it should be deemed advisable to simplify the construction and reduce cost, or meet special considerations and requirements in use, or in accordance with the views and wishes of the builder or purchaser of the machine. The ram 4 is shown sleeved upon one end of a post or stem 4^a having the

main portion of its length contained within an elongated socket in a carrier 4^b constructed with a strap 4^c encircling the eccentric 4^d on the operating shaft 3. The eccentric in its rotation gives a reciprocatory movement to the carrier 4^b, which carries the post 4^a and ram with it in its movements, thereby causing the ram to alternately approach the die and recede therefrom. To guide the ram in its movements a radius arm or lever 4^e, which is hung by means of a pivotal shaft 4^f between the upper portions of the cheeks 2, 2, is connected pivotally at 4^g with the ram, as shown in Figs. 1, 4 and 5. The said radius arm or lever 4^e is of open framework construction, with the forwardly projecting ends of its side-portions arranged so that they receive between them a rearwardly projecting lug of the ram, the pivot 4^g being engaged with the said ends and the lug as shown. To secure the yielding action of the ram in pressing the work against the die, the post 4^a by which the ram is more immediately supported is made movable within the socket of the carrier 4^b, and a cushioning means is combined therewith. This cushioning means comprises in the present instance a spring-controlled rocker or lever 4^h which is hung or pivoted at 4ⁱ in the lower part of the carrier 4, it having a toe 4^k which engages with the inner end of the post 4^a. The controlling spring therefor is an expanding spiral spring 4^m that is confined between the free extremity of the lever or rocker 4^h and an adjacent portion of the carrier 4^b, the opposite ends of the said spring being seated in pockets that are formed in the said end of the lever and in the said portion of the carrier respectively. The spring by its tendency to expand acts against the lever or rocker 4^h so that the toe 4^k of the latter serves to support the post 4^a and the ram 4, with the ram in its outward position relative to the carrier. When the thickness of work intervening between the ram and the die is such as to oppose sufficient resistance to the closing movement of the ram to overcome the tension of spring 4^m, the said spring yields and permits the lever or rocker 4^h to turn on its pivot 4ⁱ relative to the carrier 4^b. To enable the cushioning effect to be varied to meet requirements in practice, provision is made for adjustment of the tension of the spring 4^m. The means of adjustment comprises a pin or stud 4ⁿ which is fixed by one end to the carrier 4^b at the center of the spring-receiving cup on the carrier and projects through a hole in the lever or rocker 4^h formed concentrically with the spring-receiving pocket of the said lever or rocker. The spring 4^m surrounds the intermediate portion of the said pin or stem. The portion of the pin or stud which projects at the front of the lever or rocker 4^h is screw-threaded and has applied thereto adjust-

ment and check-nuts 4^a, 4^b. By backing off the said nuts the said spring is permitted to expand more or less and thereby its tension is reduced, while by turning the said nuts inward along the pin or stud 4^a so as to compress the spring more or less the tension of the spring is increased. Adjustability of the ram upon the post 4^a toward or from the die to suit the thickness of the work is secured by screw-threading the outer portion of the said post and applying thereto a nut 4^c and connected gear 4^d, shown best in Fig. 1, the said nut and gear serving as a collar to fix the position occupied by the sleeve of the ram upon the post. By turning the nut around the post, it and the ram are shifted lengthwise of the post. To provide for conveniently turning the nut by hand, a pinion 4^e is mounted alongside the nut-gear 4^d and in engagement therewith, this pinion having a thumb wheel 4^f which enables it to be turned manually for the purpose of rotating the nut 4^c. The pinion 4^e and thumb wheel 4^f are mounted upon the carrier 4^b by means of a journal 4^g projecting from them and entering a bearing in a projecting portion of the carrier, in which bearing it is retained by means of the inner end of a screw 4^h, the said end entering an annular groove around the journal. To prevent the post from rotating while the adjustment nut 4^c is being turned, a screw 4ⁱ is applied to the side of the said post, its end projecting from the post into a longitudinal slot 4^j formed in the carrier 4^b. This slot permits the post to move lengthwise within the socket of the carrier as the spring 4^m yields under the closing pressure and expands when such pressure is relieved.

Suitable back-stops or gages 10, 10^a, are combined with the ram 4, at opposite sides thereof, to determine by engagement with the rear edge of the work the proper position of the work when applied to the face of the ram. Each of these gages or back-stops has a body-plate which is applied to the corresponding end or side of the ram and attached thereto by means of screws 10^a, 10^b, the said plate being slotted at 10^b to permit the gage or back-stop to be adjusted in the direction from front to rear or vice versa.

The strip *a* of transfer material passes from the source of supply through the guide-system A, past and in engagement with the pull-off 7, then forward between the ram 4 and die 5, to and around the curved portion of a guide 11 adjacent the die, then rearward through the guide-system B, and then between the feed-rolls 8 and 9.

The guide-system A is located at the supply-side of the die and ram. It includes a backing-plate 12, which occupies an upwardly inclined position and serves to sup-

port the strip *a* as the latter passes through the said guide-system. The guide-system A also includes edge-guides 12^a, 12^b, for the strip which are shown best in Fig. 3. The said edge-guides are located at opposite sides 70 of the path of the strip *a*. They are adjustable toward and from each other to suit different widths of strip. With the edge-guides are combined means for holding them in parallelism with each other, maintaining them in parallelism in all positions of adjustment, and keeping them securely in their adjusted position. To hold the edge-guides 12^a, 12^b, in their working positions and parallel with each other, as well 75 as maintain them in parallelism in the different positions of adjustment, each edge-guide is connected with the plate 12 by a pair of parallel-motion links 12^b, 12^c, shown best in Fig. 3. Movement of the 80 edge-guides in the direction of their length will cause the parallel-motion links to swing about the points of pivotal connection with the plate 12, with resulting shift of the edge-guides toward or from each other, according to the direction of movement. Thereby the adjustment of the edge-guides for varying the distance between them to suit the width of the strip *a* is effected. To insure movement of the edge-guides in unison and cause them to move inward or outward simultaneously and to the same extent in being adjusted, the two edge-guides are connected by means of links 12^a, 12^c, or in other convenient manner, with an intermediate located longitudinally arranged bar 12^d. This bar is mounted conveniently in position by being supported upon cross-bars 12^e, 12^f, which in this instance respectively lie upon the upper and lower ends, 85 respectively, of the edge-guides 12^a, 12^b. The cross-bars 12^e, 12^f, are held in place by means of screws 12^h, 12ⁱ, the stems of which pass through holes in the opposite ends of the said cross-bars and enter threaded holes 90 that are tapped in the marginal portions of the plate 12. The longitudinal bar 12^d is held in place upon the cross-bars 12^e, 12^f, by means of screws 12^f, 12^g, the stems of which pass through longitudinal slots 12^e, 12^f, in the bar 12^d and enter threaded holes 95 in the cross-bars 12^e, 12^f. The slots 12^e, 12^f, provide for longitudinal shift of the bar 12^d, and thus permit of the adjustment of the edge-guides toward or from each other. 100 After having been adjusted, the edge-guides 12^a, 12^b, may be securely fixed in place, either by tightening the screws 12^f, 12^g, so as to clamp the bar 12^d to the cross-bars 12^e, 12^f, and thereby hold the bar 12^d from 105 longitudinal movement, or, without tightening the said screws 12^f, 12^g, by tightening the screws 12^h, 12ⁱ, so as to cause the cross-bars 12^e, 12^f, to press upon the edge-guides 12^a, 12^b, and clamp the latter firmly against 110

the outer surface of the backing-plate 12. This latter mode of holding the edge-guides in their adjusted position has the advantage that as a result of the edge-guides being 5 clamped firmly against the surface of the backing-plate 12 it is rendered impossible for either edge of the strip *a* to enter between one of the edge-guides and the said backing-plate. When it is desired to adjust 10 the edge-guides toward or from each other, it is of course necessary that the pressure of the cross-bars 12^g, 12^g, upon the edge-guides should be sufficiently relaxed to permit the edge-guides to slide beneath the 15 cross-bars, and that the adjustment bar 12^d should be free to slide longitudinally. The upper portion of the backing-strip 12 is curved forward toward the die and ram to provide a curved guiding surface for the 20 strip *a* as it changes direction in leaving the guide-system A.

Between the guide-system A and the pull-off 7 the strip *a* is engaged by a device 13 which serves to take-up the slack in the portion 25 of the strip which is passing through the machine. Thereby the strip is maintained at uniform tension within the machine, and uniformity in the extent to which the strip is advanced relative to the die at 30 each feed-movement of the feed-rolls is insured. This take-up 13 in the present instance is in the form of a swinging bail comprising a transverse portion which rests upon the strip adjacent the curved upper 35 portion of the backing-plate, and side-arms which are engaged pivotally with lugs 12^l, 12^l, upon the upper portion of the said backing-plate. The said bail rests by its weight upon the strip between the pull-off and the 40 point at which it leaves the backing-plate 12, and operates to maintain the strip uniformly taut. When the working of the parts tends to slacken the portion of the strip that is passing through the machine the 45 bail swings so as to form a bend in the strip between the backing-plate 12 and the pull-off, thus taking up the slack and maintaining the strip at substantially uniform tension. In practice, a slight drag is applied to 50 the strip before it arrives at the take-up device, whereby the strip is held back at the supply-side of such device so that the latter operates effectively to take-up the slack arising within the machine as far as the feed- 55 rolls. This drag will be produced by applying in any convenient manner a slight resistance to oppose the travel of the strip from the source of supply through the guide-system A. I have herein shown provision 60 for creating and applying the said drag in the form of a small weight, 13^x, Fig. 3, resting upon the strip adjacent the lower cross-bar 12^g.

A continuation of the curved guide 11, 65 extending upwardly and rearwardly above

the die and die-support, constitutes a backing-plate for the guide-system B. The latter, as shown best in Fig. 2, corresponds in general construction with guide-system A, and comprises the parallel edge-guides 11^a, 70 11^a, parallel-motion links 11^b, 11^b, etc., connecting-links 11^c, 11^c, adjustment-bar 11^d slotted at 11^e, 11^e, screws 11^f, 11^f, and transverse-bars 11^g, 11^g. The upper end-portion of the guide and backing-plate 11 is curved 75 toward the entrance between the feed-rolls 8, 9, to provide for a gradual change of direction of the strip as it passes from guide-system B to the feed-rolls.

The feed-rolls 8, 9, are located at the rear 80 of the guide-system B, adjacent the curved end of the backing-plate 11. The shaft 8^a of the feed-roll 8 is mounted in bearings in opposite stands 14, 14, which are made fast to the upper portions of the cheeks 2, 2. The 85 shaft 9^a of the roll 9 projects at its ends or journals into slots 14^a in the said stands, and within each of the said slots a block 9^b is held against the corresponding end-portion or journal by an expanding spiral spring 90 9^c, the tension of which is regulated by means of an adjusting screw 9^d. By the tendency of the springs to expand the roll 9 is pressed toward the roll 8 so as to enable the rolls to engage properly with the strip *a* 95 passing between them and act to feed the strip along when the rolls are rotated. To enable the rolls to be separated from each other whenever desired, a roll-separator is provided. In this instance it consists of a 100 U-shaped frame 15 hung upon a transverse wire or rod 15^a extending from one stand 14 to the other, the said frame having side-arms 15^b, 15^b, which pass down alongside the 105 ends of roll 9 and are formed with cam-portions 15^c, 15^c, which are disposed in front of the journals of such roll. A handle 15^d is provided on the frame 15, by means of which the latter may be rocked to cause the cams to act against the said journals to press the roll 9 away from the roll 8, overcoming the resistance offered by the springs 9^c, 9^c. The cam-portions 15^c, 15^c, are formed with projecting portions which act against the 110 journals to prevent excess movement of the frame which would disengage the said cam-portions altogether from the journals.

The feed-rolls are rotated intermittently automatically by means of suitable actuating devices. Herein the said actuating devices 115 comprise a crank 16 carried by shaft 3, connected by a rod 17 with a lever 18 hung upon one projecting end-portion of the shaft 8^a of feed-roll 8. The said lever 18 carries an eccentric friction-dog 18^a that is rotated by 120 a spring 18^x, Fig. 2, to cause its eccentric portion to engage with the periphery of a wheel 18^b fixed upon the said end-portion. Through the described devices an intermittent movement of rotation is transmitted 130

to the feed-roll 8 from the operating shaft 3. The feed-rolls 8, 9, are geared together by spur-gears 19, 19, fixed upon their shafts so that they thereby positively are caused to 5 rotate in unison, slip of one roll relative to the other being avoided. An eccentric friction-dog 18^a mounted upon the adjacent stand 14 on the stem of a screw 18^a and rotated by a spring 18^b, Figs. 2 and 3, to cause 10 its eccentric portion to engage with the periphery of wheel 18^b, serves to prevent backward rotation of the feed-roll 8. To provide for varying the extent to which the strip α is moved along at each feed-movement, I employ 15 a crank 16 of adjustable throw. In this instance the carrier 16^a of the crank-pin is slotted lengthwise at 16^b and secured to a face-plate 16^c on one end of shaft 3 by means of a screw 16^d passing through slot 16^b 20 into the said face-plate. This construction permits the carrier 16^a to be adjusted diametrically of the shaft 3 so as to enable the crank-pin to be set at the distance from the axis of said shaft 3 which is necessary to 25 give the proper throw to secure the desired extent of feed-movement.

To hold the carrier 16^a from turning relative to the face-plate, but still permit of the adjustment of the carrier diametrically with 30 relation to the shaft 3, I may employ any convenient guiding arrangement in connection with the carrier and face-plate. In the present instance pins 16^e, 16^f, are oppositely located upon the carrier and parallel slots 35 16^e, 16^f, are formed in the face-plate. These slots extend parallel with the diametrical line on which the crank pin is adjustable, and at opposite sides of the said line and the pins work in the said slots 16^e, 16^f. 40 To enable the feed-rolls to be rotated manually for the purpose of advancing the strip α at will, the roll 8 is furnished with a thumb-wheel 20, Figs. 2 and 3, fixed upon one projecting end-portion of its shaft 8^a. 45 When it is desired to make a backward or reversed shift of the strip, the rolls are separated by means of the roll-separator so as to release their grip upon the strip and permit it to be adjusted by hand.

50 As the ram closes against the die the pull-off 7 operates to pull from the source of supply and through the guide-system A a sufficient length of the strip α for the next feeding movement of the latter past the die, 55 and as the ram separates from the die the pull-off slackens the strip within the machine concurrently with a feed-movement of the feed-rolls acting to draw the strip past the die. The pull-off and slackening 60 action are provided for by mounting the pull-off 7 upon the radius-arm or frame 4^e, the latter being linked at 4^e to the ram, as already explained, so as to be swung by the movements that are imparted to the ram. 65 Thereby the pull-off is operated in unison

with and by the ram. Each movement of rotation of the feed-rolls coincides with the slackening of the strip by the reverse movement of the pull-off, and consequently the feed-rolls merely operate to draw forward 70 the slack strip without straining or tending to tear the same. The extent of the turning movement of the feed-rolls determines the extent of the feed of the strip.

As shown in Figs. 1, 4 and 5, the curved 75 forward extremity of the backing-plate and guide 11 extends down in front of the forward end of the die-support, and normally occupies the position in which it is shown in Fig. 4 in relation to the die. In this position a portion of it projects a little below the die, so that such portion holds the strip α separated from the face of the die. The said backing-plate and guide is movably mounted, and to it are given movements which at 80 the time of the closing of the ram toward the die for the impression cause the guide to recede relative to the die as in Fig. 5 so as to carry the said strip close to the face of the die, or into contact with such face; and subsequently, as the ram moves away from the die after the impression, causes the guide to follow the ram part way so as to detach the strip from the face of the die and separate it therefrom. The further receding movement of the ram carries the latter away from the strip, as shown in Fig. 4. For the movable mounting of the guide, the combined backing-plate and guide 11 is supported 85 pivotally at 11^x upon small stands 11^y, 11^y, 100 rising from the tops of the cheeks, 2, 2. The required movements are communicated to the backing-plate and guide, to rock the same upon its pivotal mounting, through 90 connections between the same and the radius-arm or lever 4^e of the ram 4. The said connections include a link 11^w extending from the rear portion of the combined backing-plate and guide to a portion of the radius-arm or lever 4^e at the rear of its pivot 105 4^e. To provide for adjustment of the guide with reference to the die and the front end of the die-support, the link 11^w is made adjustable in length by being formed in two 110 parts or members which respectively are pivotally joined to the combined backing-plate and guide, and radius-arm or lever 4^e, respectively, and connected together by means of screws 11^v, 11^v, one of the two link-members being longitudinally slotted to permit the said members to be adjusted relative to each other so as to vary the length of the link. By lengthening or shortening the link 11^w the downturned end of the guide 11 is 115 lowered or raised relative to the die. 120

Simultaneously with the receding movement of the ram and the accompanying movement of the guide by which the strip α is separated from the face of the die, and detached therefrom in case it should tend to 125 130

cling thereto, the forward pull upon the said strip produced by partial rotation of the feed-rolls operates to detach the strip *a* from the leather or other material which has been 5 embossed or printed, in case it should tend to adhere thereto. After the feed movement by which the portion of the strip *a* which is to be used in making the next impression is brought into position between the die 5 and 10 the ram, the strip is held taut between the pull-off 7 and the curved lower end of the guide 11, so that thereby it is held definitely against displacement as by a draft of air or by contact of the work therewith while 15 the latter is being placed in position to be operated upon.

A difficulty experienced in feeding a strip of some length between a pair of feed-rolls is the tendency of the strip to work edge- 20 wise progressively in one direction or the other. I overcome this difficulty through the employment of an automatic guide by which tendency of the strip to swerve from the proper path is corrected. This portion 25 of the invention involves broadly the employment of automatic strip-guiding means controlled by the strip and acting to restore the latter automatically to the proper path of travel in case it swerves from such 30 path. In the illustrated embodiment of the invention the feed-roll 8 is arranged to counteract the said tendency. For the said counteraction, I construct and combine the roll 8 and its supporting shaft or arbor 35 8^a so that when the strip *a*, in being fed, swerves toward one side or the other, the strip itself shall swing the roll into a position so inclined relative to the length of the strip that the rotation of the roll will 40 carry the strip automatically back into the proper path. Referring now to Figs. 4, 5 and 6, it will be observed that in Fig. 6 the longitudinal bore that is made through the roll 8 for the reception of the shaft or 45 arbor 8^a is larger in diameter than the portion of the latter which occupies the main length of the said bore, and that at mid-length of the roll the shaft or arbor is formed with an annular enlargement 8^b 50 having a transversely rounded periphery and resembling the middle zone of a sphere. The portion of largest diameter of this enlargement fits the bore of the roll 8 at mid-length of the roll. A screw 8^c has its stem 55 screwed into the enlargement, while its rounded or ball-shaped head occupies a radial hole 8^d in the roll. The said head prevents the roll from displacement longitudinally of the shaft or arbor 8^a, while 60 the construction permits the roll to swivel relative to the shaft or arbor. In the operation of the machine, so long as the middle of the width of the strip *a* corresponds in position with the middle of the width of 65 the enlargement 8^b, equal portions of its

width will lie at opposite sides of the point of swiveling of the roll, which will balance the action upon the roll so that the latter will occupy a position in which its axis remains at right angles to the length of the strip and coincides with that of the shaft or arbor 8^a, being parallel with that of the roll 9 and its shaft or arbor. When, however, the strip swerves sidewise in one direction or the other, the preponderance of 70 width of the portion of strip at the side of the swiveling point toward which the strip has swerved will carry the corresponding end of the roll 8 forward, thereby causing the said roll to swing into a forwardly inclined or angular position. The result of this will be that rotation of the roll in such forwardly inclined or angular position will exert a tendency to cause the strip to travel back to the middle position again. In this 75 way the roll will automatically guide the strip so that it normally will travel in the predetermined path. The side-guides of the two guide-systems A, B, are located at equal distances from the proper position for 80 the middle line of the strip, and inasmuch as the said guides are arranged to move equally in opposite directions from or toward said middle line in their adjustments, and to remain parallel to each other in all 85 their positions of adjustment, the said adjustments have no disturbing effect upon the path of travel of the strip which would interfere with the attainment of the desired results in automatically guiding the strip 90 by means of the swiveling roll 8. 100

For some classes of work, the strip *a* of transfer material consists of a strip of paper treated with paraffin charged at one surface of the strip with the gold or other 105 printing substance. Proximity of the strip to the heater has the effect of softening the paraffin and decreasing its hold upon the gold or other printing substance. In other words the effect of the heat from the 110 heater is to render it easier for the gold, or other printing substance, to strip from the paper-backing. The result of this, in the absence of means to counteract this 115 tendency, is a liability of the printing substance to strip from the backing alongside the lines of the imprint made upon the leather or other work operated upon. When the feed-movements of the strip are closely proportioned to the size of the face 120 of the die, so as to economize in the use of the printing substance this stripping of the printing substance from the backing alongside lines of the imprint upon the work will deprive portions of the backing 125 within the limits of the next succeeding impression of portions of their charge of the printing substance and consequently the succeeding imprint will be imperfect. To prevent this tendency, a cooling device is 130

provided by means of which the softening of the paraffin is prevented. This cooling device comprises in the present instance a mouth-piece 20 arranged to discharge a stream of air upon the portion of the strip *a* which is adjacent the die and heater. The said mouth-piece is shown arranged above the pull-off 7, and so as to direct the said stream upon the reverse side of the strip 10 below the heater. The mouth-piece 20 is attached to a short pipe 20^a carried by the radius-arm or lever 4^c. In practice, a conducting pipe or tube (not shown) will extend from the said pipe 20^a to a pump (not shown) or other source of supply for air under pressure.

The illustrated machine is adapted for use in operating upon the interior surfaces of the uppers of shoes by reason of the fact 20 that the die-support and the die are of width and proportions adapting them to be received within the top of an upper, and the strip *a* feeds from the rear, forward past and around the die and the front end of the 25 die-support, and then rearward relative thereto. If the said strip were fed laterally from a source of supply at one side or the other of the die and die-support, the portions of the strip stretching laterally outward from the die at one or both sides of the latter would interfere with the application of a shoe-upper to the machine for the purpose of being embossed or printed.

I claim as my invention:—

35 1. In an embossing or printing machine, the combination with a die and presser-member, and means for feeding a transfer-strip intermittently between the said parts, of a pull-off acting to pull the strip forward 40 from the source of supply during the closing together of the said parts, and to slacken the strip during the succeeding opening of such parts to facilitate the feed movement of the strip.

45 2. In an embossing or printing machine, the combination with a die and presser-member, and means for feeding a transfer-strip intermittently between the said parts, of a pull-off acting at the supply-side of the 50 die and presser-member to pull the strip forward from the source of supply during the closing together of the said parts and to slacken the strip during the succeeding opening of the latter to facilitate the feed-movement of the strip.

55 3. In an embossing or printing machine, the combination with a die and presser-member, and means for feeding a transfer-strip intermittently between the said parts, of a pull-off actuated by the movement of one of the latter to pull the strip forward 60 from the source of supply to facilitate the feed-movement of the strip.

4. In an embossing or printing machine, 65 the combination with a die and presser-mem-

ber, and means acting at the delivery side of the said parts to feed a transfer-strip intermittently between them, of a pull-off actuated by the movement of one of such parts and acting at the supply side of the latter 70 to pull the transfer-strip forward from the source of supply to thereby facilitate the feed-movement of the strip.

5. In an embossing or printing machine, the combination with a die and presser-member, and means acting at the delivery side thereof to feed a transfer-strip intermittently between them, of a pull-off actuated by the movement of one of the said parts to pull the strip forward from the 80 source of supply at the supply side of the die and presser-member during the closing together of the said parts, and to slacken the strip during the succeeding opening of such parts to facilitate the feed-movement of the 85 strip.

6. In an embossing or printing machine, the combination with a die and presser-member, a swinging arm controlling the path of movement of one of said parts in 90 closing and opening, and means for feeding a transfer-strip intermittently between the die and presser-member, of a pull-off operatively combined with the said arm and acting to pull the transfer-strip forward from 95 the source of supply.

7. In an embossing or printing machine, the combination with a die and presser-member, a swinging arm controlling the path of movement of one of said parts in 100 closing and opening, and means for feeding a transfer-strip intermittently between the die and presser-member, of a pull-off carried by the said arm and actuated by the movement of the latter to pull the transfer- 105 strip forward from the source of supply.

8. In an embossing or printing machine, the combination with a die and presser-member, and means for intermittently feeding a transfer-strip between them, of a pull-off by which the transfer-strip is drawn forward from the source of supply and slackened to facilitate the feeding of the strip, and a yielding take-up for taking-up the slack of the said strip and maintaining the 115 strip under substantially uniform tension.

9. In an embossing or printing machine, the combination with a die and presser-member, and means for intermittently feeding a transfer-strip between them, of a pull-off by which the transfer-strip is drawn forward from the source of supply to facilitate the feeding of the strip, and a yielding take-up acting upon the strip at the supply side of the said pull-off for taking-up the slack 120 of the strip within the machine and maintaining the strip under substantially uniform tension therein.

10. In an embossing or printing machine, the combination with a die and presser-mem- 125 130

- ber, and means for intermittently feeding a transfer-strip between the said parts, of a pull-off by which the transfer-strip is drawn forward from the source of supply and slackened to facilitate the feeding of the strip, and a swinging take-up for controlling the slack of the said strip and maintaining the latter under substantially uniform tension.
- 10 11. In an embossing or printing machine, the combination with a die and presser-member, and means for feeding a transfer-strip between them, of a strip-guide normally occupying a relative position in which it holds
- 15 the strip separated from the face of the die, relative movement between the strip-guide and die carrying the strip close or into contact with the face of the die at the time of the impression and detaching and moving it away therefrom following the impression.
12. In an embossing or printing machine, the combination with a die and presser-member, of a strip-guide normally occupying a relative position in which it holds the strip separated from the face of the die, relative movement between the strip-guide and die carrying the strip close or into contact with the die at the time of the impression and separating it therefrom following the impression, and strip-feeding means acting simultaneously with the relative movement tending to separate the strip and die from each other.
13. In an embossing or printing machine, the combination with a die and presser-member, of a strip-guide actuated through the closing movement of the said parts to carry a transfer-strip close or into contact with
- 40 the die and acting during the opening movement thereof to separate the strip from the die, and strip-feeding means.
14. In an embossing or printing machine, the combination with a die and presser-member, of a strip-guide actuated by the presser-member to carry a transfer-strip close or into contact with the die as the presser-member approaches the die and to separate the strip from the die as the presser-member recedes from the latter, and strip-feeding means.
15. In an embossing or printing machine, the combination with a die and relatively movable presser-member, and a swinging arm connected with the said presser-member, of a strip-guide operatively connected with the said arm and moved therefrom to carry a transfer-strip close or into contact with the die as the presser-member approaches the die and to separate the strip from the die as the presser-member recedes from the latter, and strip-feeding means.
16. In an embossing or printing machine, the combination with a die and relatively movable presser-member, of a swinging arm
- 5 moving in unison with the said presser-member, a pull-off actuated by the said arm to pull a transfer-strip forward from the source of supply, a strip-guide actuated by the said arm to carry the transfer-strip close or into contact with the die as the presser-member approaches the die and to separate the strip from the die as the presser-member recedes from the latter, and strip-feeding means.
17. In an embossing or printing machine, the combination with a die and movable presser-member, of a pull-off operatively combined with the said presser-member and actuated thereby to pull a transfer-strip forward from the source of supply, a strip-guide also operatively combined with the said presser-member and actuated thereby to carry the transfer-strip close or into contact with the die as the presser-member approaches the die and to separate the strip from the die as the presser-member recedes from the latter, and strip-feeding means.
18. In an embossing or printing machine, the combination with a die and movable presser-member, of a strip-guide operatively combined with the said presser-member and actuated thereby to carry a transfer-strip close or into contact with the die as the presser-member approaches the die and to separate the strip from the die as the presser-member recedes from the latter, means to adjust the said strip-guide relatively toward and from the face of the die, and strip-feeding means.
19. In an embossing or printing machine, the combination with a die and movable presser-member, and a swinging arm connected with the said presser-member, of a pivotally mounted strip-guide, means connecting the said strip-guide with the said arm to actuate said strip-guide to carry a transfer-strip close or into contact with the die as the presser-member approaches the die and to separate the strip from the die as the presser-member recedes from the latter, means to adjust the strip-guide relatively toward and from the face of the die, and strip-feeding means.
20. In an embossing or printing machine, the combination with the impression-members, of a swiveling roll with which the transfer-strip makes contact, given a position inclined across the path of movement of the transfer-strip when the transfer-strip swerves widthwise, and acting to automatically restore the strip to the proper path of movement.
21. In an embossing or printing machine, the combination with the impression-members, of a pair of feed-rolls, one thereof mounted to swivel in a plane parallel with the path of movement of the transfer-strip, controlled as to the angle with which its axis crosses the said path by the transfer-strip,

- and acting to automatically restore the strip to the proper path of movement.
22. In an embossing or printing machine, the combination with the impression-members, means for guiding a strip of transfer-material between them, and a heater in connection with said impression-devices, of means for cooling the portion of the said strip which is adjacent the impression-point.
23. In an embossing or printing machine, the combination with the impression-members, means for guiding a strip of transfer-material between them, and a heater in connection with said impression-devices, of means for delivering a cooling jet upon the portion of said strip between the adjacent members.
24. In an embossing or printing machine, the combination with the impression-members, and a heater in connection with the latter, of a jet-nozzle moving with one of said members and adapted to deliver a cooling jet upon transfer-material occupying a position between the impression-members.
25. In an embossing or printing machine, the combination with a die and presser-member, an arm connected with one thereof, and a heater for the said die, of a jet-nozzle carried by the said arm and adapted to direct a cooling jet upon transfer-material occupying a position between the die and presser-member.
26. In an embossing or printing machine, the combination with a die and presser-member, a heater for the said die, and guides for a strip of transfer-material at front and rear respectively of the die, of a cooling device having an orifice adapted to deliver a cooling jet upon the strip adjacent the die.
27. In an embossing or printing machine, the combination with a presser-member, and a post or stem therefor, of a carrier receiving the said post or stem, means for actuating said carrier for the impression, and a spring-actuated rocker movably mounted upon the carrier and engaging the said post or stem, constituting a cushioning means for the presser-member.
28. In an embossing or printing machine, the combination with a presser-member, and a post or stem therefor, of a carrier receiving the said post or stem, means for actuating said carrier for the impression, a spring-actuated rocker movably mounted upon the carrier and engaging the said post or stem, constituting a cushioning means for the
- presser-member, and means for adjusting the spring-tension.
29. In an embossing or printing machine, the combination with a presser-member, of a screw-threaded support on which said member is sleeved, an adjusting collar or nut engaging the threaded portion of the said support, and an adjustment hand-wheel geared to the said collar or nut.
30. In an embossing or printing machine, the combination with a die-support and die adapted to enter within the top of the upper of a shoe, and a presser-member coöperating with the said die in making an impression, and means for guiding a strip of transfer material from the rear forward to and around the die and rearward therefrom.
31. In an embossing or printing machine, the combination with a die-support and die adapted to enter within the top of the upper of a shoe, and a presser-member coöperating with the said die in making an impression, the said parts constructed to permit the work to be inserted upwardly between the presser-member and die, and means for guiding a strip of transfer material from the rear forward to and around the die and rearward therefrom.
32. In an embossing or printing machine, the combination with a die-support and die adapted to enter within the top of the upper of a shoe, and a presser-member coöperating with the said die in making an impression, means for guiding a strip of transfer material from the rear forward to and around the die and rearward therefrom, and means for intermittently feeding the said strip to and past the die.
33. In an embossing or printing machine, the combination with a die-support and die adapted to enter within the top of the upper of a shoe, and a presser-member coöperating with the said die in making an impression, the said parts constructed to permit the work to be inserted upwardly between the presser-member and die, means for guiding a strip of transfer material from the rear forward to and around the die and rearward therefrom, and means for intermittently feeding the said strip to and past the die.
